[57] CLAIM

The ornamental design for a fishing lure, as shown and described.

DESCRIPTION

FIG. 1 is a front perspective view of a first embodiment of a fishing lure showing my new design;
FIG. 2 is a top plan view thereof;
FIG. 3 is a side elevational view thereof;
FIG. 4 is a bottom plan view thereof;
FIG. 5 is a front elevational view thereof;
FIG. 6 is a rear elevational view thereof;
FIG. 7 is a top plan view of a second embodiment of a segmented fishing lure with arcuate side portions of this invention distinguished from the first embodiment by having a forward segment with an arcuate left side portion and a rearward segment with an arcuate right side portion; and,
FIG. 8 is a bottom plan view of the invention of FIG. 7.

Fig. 1.Fig. 5.Fig. 6.Fig. 2.Fig. 3.Fig. 4.Fig. 7.Fig. 8.
